UNITED STATES PATENT OFFICE

2,026,485

CARBURETOR

Walter H. Weber, Detroit, Mich., assignor to Detroit Lubricator Company, Detroit, Mich., a corporation of Michigan

Application May 5, 1932, Serial No. 609,411

5 Claims. (Cl. 261—50)

My invention relates to new and useful improvements in carburetors, and more particularly to a carburetor for supplying an explosive mixture to an internal combustion engine.

5 An object of my invention is to provide a carburetor in which the liquid fuel will be efficiently nebulized and equally distributed throughout the column of supplied air.

10 Another object is to provide a carburetor in which a proper ratio of fuel to air for road loads may be obtained while maintaining an economical ratio of fuel to air for engine idling speeds.

15 The invention consists in the improved construction and combination of parts, to be more fully described hereinafter and the novelty of which will be particularly pointed out and distinctly claimed.

20 In the accompanying drawing, to be taken as a part of this specification, I have fully and clearly illustrated a preferred embodiment of my invention, in which drawing—

25 Figure 1 is a top plan view of a carburetor embodying my invention, but having the throttle valve partly broken away;

Fig. 2 is a view in end elevation and partly in section on the line 2—2 of Fig. 1, and

30 Fig. 3 is an enlarged detail view in section on the line 3—3 of Fig. 2.

Referring to the drawing by characters of reference, 1 designates, generally, a carburetor casting comprising a base or bottom portion 2 and a throttle body portion 3. The portion 2 includes

35 an air chamber 4 having an air inlet 5 which preferably opens laterally thereinto, the chamber

preferably being substantially rectangular in horizontal cross-section and having an open top defining the outlet therefrom. Rising from the bottom wall of the chamber 4 there is a sleeve

40 or tubular member 6 which is of enlarged internal diameter at its lower end for substantially half its height, as at 7, to provide a dash-pot chamber. Within the member 6 there is fitted

45 for longitudinal reciprocation a tubular member 8 having a longitudinal, open-ended bore or passage 9 therethrough, with its lower, open end defining a metering orifice or port. The lower end of the tubular member terminates in the

50 chamber 7 and has an annular flange 10 serving as a dash-pot piston or plunger. The upper end of member 8 projects above the sleeve member

55 and is preferably screw-threaded to receive a nozzle 11, which is preferably substantially cylindrical and has a substantially horizontal, circumferential groove 12 at its lower end. The nozzle 11 has a cylindrical recess 13 in its under side

into which the upper end of the sleeve member 6 projects. Extending into the nozzle from the end wall or base of the recess, there is a stepped bore 14 concentric with the passage 9 and which provides a downward facing shoulder 15. A disc 5 or plate 16 is positioned in the bore 14 and seats at its periphery against the shoulder, to which it is tightly clamped by the upper end of the member 8 on which the disc rests. The disc 16 is provided with a calibrated orifice 17. The 10 inner or upper end of the bore 14 terminates within the nozzle in communication with a plurality of end slots 18 extending radially therefrom. The slots 18 are preferably diametral, opening through the side walls of the nozzle and 15 also through the top end of the nozzle.

A plate member 19 seats upon the portion 2 and supports the portion 3, which at its lower portion is substantially rectangular internally, as at 20. The member 19 is clamped tightly between the portions 2, 3 and all are secured rigidly together by bolts or screws 21. The member 19 has a substantially rectangular aperture 22 therethrough in registry with the air chamber and the lower portion of the throttle body. At 25 the opposite side edges of the aperture 22 which are transverse to the air inlet, there are upward extending, substantially parallel guide plates 23. The opposing inner faces of the plates 23 are preferably provided with air deflecting members 24. The members 24 converge upward toward each other from the bottom edge of the plate aperture 22 so that the air passage between the members 24 tapers or converges upward.

Air flow through the aperture in plate member 19 is controlled by air valve means, preferably in the form of pivoted or hinged flap valves or vanes 25. Each of the vanes is journaled at its lower edge on a shaft 26 extending transversely to the guide plates 23 at the sides of and within the aperture 22, the shafts being supported at their ends in bearing apertures in the plate member 19. The vanes 25 are inclined upward and abut or engage each other, as at 25a, to close the air inlet to the mixing chamber 27 in conjunction with the guide plates 23, the outlet from chamber 27 being controlled by a throttle valve 28. The deflecting members 24 are positioned beneath the vanes 25 and have their top side edges transverse to the plane of the opposed faces of plates 23 and converging upward to an apex substantially at the meeting edge of the vanes 25, Fig. 2, so that the members 24 are substantially triangular in front elevation. Each of the vanes 25 is provided on its under face with 55

a lever arm 29, preferably in the form of a vertical web terminating in a finger which extends into the nozzle groove 12, so that the vanes and nozzle are interconnected for simultaneous movement. The top slotted end of the nozzle extends upward into an aperture 30 through the meeting edges of the vanes, so that the bore of the nozzle is in open communication with the mixing chamber through the medium of the slots 18. The diameter of the aperture 30 is greater than the diameter of the nozzle, so that an annular air passage surrounds the nozzle when the vanes are closed. The slots 18 are of sufficient length or depth to extend below the vanes so that air may directly enter certain of the slots from the air chamber. The vanes are normally urged to closed position by a spring 31 positioned in the dash-pot chamber, the spring preferably being a helical coil spring surrounding member 8 and held under compression between the top wall of the chamber and the flange 10. It may be noted that the side edges of the deflecting members 24 converge upward parallel with the undersurfaces of the vanes, so that the vanes can close. The bottom end of the dash-pot chamber is closed by a plug 32 in which is adjustably supported a needle valve or metering pin 33 which extends upward into the bore 9 and cooperates with the lower, open end of the bore to meter fuel flow to the nozzle.

Fuel is supplied to the bore 9 from a constant level float chamber or reservoir 34 carried by the bottom portion 2, and preferably having a part of its wall common to the air chamber wall, as at 35. The sleeve member 6 has a port 36 in its side wall below the piston 10, the port communicating with a conduit 37 opening into the reservoir.

The operation of my carburetor is as follows: With the vanes closed, as shown, the metering pin 33 is adjusted to provide the proper quantity of fuel relative to the air admitted to the mixing chamber through the slots 18, which mixture of air and fuel will be the desired richness for efficient operation of the engine at idling speeds. If this adjustment of the metering pin does not afford the proper mixture for normal road loads on the engine, the depth of the slots 18 is changed to regulate the quantity of air admitted at idling speeds, thus if the setting of the metering pin provides too lean a mixture, i. e., deficient in fuel, at normal road loads, the depth of slots 18 is increased to admit more air at idling to the mixing chamber. This requires that the metering pin 33 be adjusted to admit more fuel at idling, and consequently with this new adjustment more fuel will be admitted at normal road loads. It will thus be seen that the use of the slots 18 provides means for regulating the ratio of fuel to air for normal carburetor operation. When the engine has been started, the throttle valve 28 being in closed idling position, the suction in the mixing chamber 27 acting on the air valves 25 will be insufficient to lift or open the valves against the force of spring 31 and the drag of the piston 10. Air entering the chamber 4 will pass upward and be deflected toward the nozzle by the members 24 and by the undersurface of the valves 25. This air from the inlet 5 will enter the slots 18 and issue in a plurality of vertical streams extending across the full width of the top face of the nozzle. The air entering the slots will aspirate fuel from the nozzle bore 14, which fuel will be disseminated and nebulized by the intersecting air streams and be discharged there-

with as an intimate mixture from the slots and through the aperture 30 into the mixing chamber. This action of the intersecting vertically moving air streams in the slots 18 will be substantially the same irrespective of the opening of the vanes. As the throttle is opened, the suction in the mixing chamber will increase and cause opening of the vanes. As the vanes open, dependent on the suction, the lever arms 29 will raise the nozzle 11 and member 8 relative to the valve 33 to increase the area of the fuel passage around the valve 33, resulting in an increased discharge of fuel from the nozzle. The rate of opening and closing of the vanes is controlled by the dash-pot, as is well known in the art.

It may be noted, for the purposes of illustration solely, that for a one and three-fourths inch carburetor, in which the jet orifice 17 has a diameter of about .097 inches, the slots 18 will have a depth of about one-half inch, a width of about one sixty-fourth inch, and preferably be eight in number, equally spaced at forty-five degrees.

What I claim and desire to secure by Letters Patent of the United States is:—

1. A carburetor comprising a casing having a mixing chamber with an air inlet and a mixture outlet, a valve having an aperture therethrough and controlling air flow from said inlet to said chamber, a fuel nozzle member in said air inlet and projecting into said aperture for discharge into said chamber, said nozzle member having a longitudinal bore and having a longitudinally extending transverse end slot at its discharge end having an open end opening through the end face of said nozzle member and communicating on the inlet side of said valve with said bore, said slot extending into said air inlet whereby the air entering said slot and the fuel leaving said bore will be discharged from said nozzle member as a thin fluid sheet.

2. A carburetor comprising a casing having a mixing chamber with an air inlet and a mixture outlet, a valve having an aperture therethrough and controlling air flow from said inlet to said chamber, a fuel nozzle member in said air inlet and projecting into said aperture for discharge into said chamber, said nozzle member having a longitudinal bore and having a plurality of longitudinal end slots at its discharge end, each slot having an open end extending through the end face of said nozzle member and radially from said bore, said slots dividing the discharge end of said nozzle member into segments and extending into said air inlet whereby the air entering said slots and the fuel leaving said bore will be discharged from said nozzle member as thin fluid sheets.

3. A carburetor comprising a casing having a mixing chamber with an air inlet and a mixture outlet, a suction operated valve having an aperture therethrough and controlling air flow from said inlet to said chamber, a fuel nozzle member in said air inlet and projecting into said aperture for discharge into said chamber, said nozzle member having a longitudinal bore and having a longitudinally extending transverse end slot at its discharge end having an open end opening through the end face of said nozzle member and communicating with said bore, said bore terminating at its discharge end in said nozzle member and intersecting said slot on the inlet side of said aperture, said slot extending longitudinally from the discharge end of said nozzle member through said aperture and into said air inlet whereby the air entering said slot and the fuel

leaving said bore will be discharged from said nozzle member as a thin fluid sheet.

4. A carburetor comprising a casing having a mixing chamber with a mixture outlet and an air inlet, a suction operated pivotally supported valve member having an aperture therethrough at its free edge and controlling air flow from said inlet to said chamber, a fuel nozzle member projecting into said aperture and having a longitudinal bore terminating in said nozzle member and short of said aperture, said nozzle member having a plurality of slots opening through the discharge end face of said nozzle member and extending longitudinally inward to said bore and into said air inlet on the inlet side of said valve member, said slots extending from said bore radially outward through the side walls of said nozzle member whereby air entering said slots will mix in said slots with fuel leaving said bore and be discharged from said nozzle member as thin fluid sheets of air and fuel.

5. A carburetor comprising a casing having a mixing chamber with a mixture outlet and an air inlet, a plurality of suction operated vane members controlling air flow from said air inlet to said chamber, said members having an aperture therethrough centrally of said chamber, a solid cylindrical fuel nozzle member in said air inlet and projecting into said aperture, said nozzle member having a bore of relatively small diameter in said nozzle member and terminating in a plurality of end slots, each slot having an open end opening longitudinally through the end face of said nozzle member for dissemination in said nozzle member of the fuel leaving said bore, said slots extending outwardly through the side walls of said nozzle member and into said air inlet whereby air entering said slots will mix in said slots with the disseminated fuel and be discharged from said nozzle member in thin fluid sheets of mixed air and fuel.
